UNITED STATES PATENT OFFICE.

JAMES FAULKNER THOMAS, OF FARIBAULT, MINNESOTA.

EXTENSION-TABLE.

1,257,149.

Specification of Letters Patent. Patented Feb. 19, 1918.

Application filed March 16, 1917. Serial No. 155,314.

To all whom it may concern:

Be it known that I, JAMES FAULKNER THOMAS, a citizen of the United States, residing at Faribault, in the county of Rice and State of Minnesota, have invented new and useful Improvements in Extension-Tables, of which the following is a specification.

This invention relates to extension tables and it has particular reference to a table of the type generally known as a library table, the object of the invention being to so construct the same that it may be extended and utilized as a dining table.

15 A further object of the invention is to produce an extension table of the type described which will be simple in construction, easily manipulated and in which the additional leaf or top member required for extension purposes will be housed below the top of the library table so as to be out of view when the table is used as a library table.

Further objects of the invention are to 25 simplify and improve the general construction and assemblage of parts constituting the improved table.

With these and other ends in view which will readily appear as the nature of the invention is better understood, the same consists in the improved construction and novel arrangement and combination of parts which will be hereinafter fully described and particularly pointed out in the claims.

35 In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings:

Figure 1 is a top plan view of the table 45 collapsed, portions of the table top and of the auxiliary leaf having been broken away.

Fig. 2 is a similar view showing the table extended.

Fig. 3 is a sectional view taken on the line 50 3-3 in Fig. 1.

Fig. 4 is a sectional view taken on the line 4-4 in Fig. 2.

Fig. 5 is a view similar to Fig. 3 but showing the table top slightly tilted preparatory 55 to extending the table.

Fig. 6 is a side view of the table with parts broken away.

Fig. 7 is a sectional view taken on the line 7-7 in Fig. 1.

Fig. 8 is a detail view in side elevation 60 illustrating the locking device.

Corresponding parts in the several figures of the drawings are denoted by like characters of reference.

The permanent frame of the improved 65 table which is rectangular in shape includes the side members 15, end members 16, legs 17, and blind end members 18, the latter being connected with the legs by lag screws 19, enabling the frame to be conveniently 70 knocked down for shipping purposes and reassembled when required. There are two movable side members, viz., the drawer front 20 and the false drawer front 21. Two extension slides of well known construction, 75 known as equalizing slides, are provided each of said slides including an inner member 22, an outer member 23, and an intermediate member 24. The extension slides are equipped with the well known equalizing 80 devices comprising pulleys 25 and wire ropes 26 or with equalizing devices of any convenient and well known construction, whereby when either the inner or the outer slide is projected with respect to the intermediate slide, its mate will be automatically 85 projected in the opposite direction. It will be understood that two extension slides are used, the intermediate member of each slide being fastened at one end to the side rails 90 15 and at the other end to a blind side rail 27. The outer member 23 of each extension slide is fastened at one end to the blind draw front 21 by suitable means such as counter-sunk screws 28.

95 The table top A is provided at the sides thereof with rims 29 and 30 of suitable width and thickness. At each end the said table top is also provided with a relatively narrow rim 31 secured thereto in any suitable manner. The extension leaf 32 may be of any desired width less than the width of the table top A enabling it to be accommodated between the side rims 29 and 30. The length of the extension leaf is substantially 100 equal to the distance between the inner faces of the end rims 31 between which the leaf is accommodated. It will be observed that by this construction, when the table is extended and the leaf 32 is placed beside the 105 110

top A, the ends of the leaf will be substantially flush with the ends of the top at one side edge thereof, the width of the end rims 31 being so slight as to cause said rims to 5 be hardly perceptible when the table is covered. One of the side rims, 29, of the table top is connected by means of hinges 33 with the inner side members of the extension slides, the parts being so constructed and ar- 10 ranged as to permit the free edge of the table top to be lifted some four or five inches when the table is to be extended. The rim 30 of the table top, when the table is col- 15 lapsed, will rest on the upper ends of two of the legs 17, adjacent to the blind drawer front 21. Supporting cleats 34 for the table drawer 35 may be mounted on the inner faces of the inner side members of the ex- 20 tension slides. The extension leaf 32, when the table is collapsed, is supported on the extension slides below the table top A, the side and end rims of which form a neat housing within which the extension leaf is 25 appropriately concealed.

Pivoted on the outer face of each of the outer side members of the extension slides are the lower ends of links 36 the upper ends of which are pivotally connected with the lugs 37 on the under face of the extension leaf 32, said links normally occupying an 30 inclined position as clearly seen in Figs. 3 and 5. One of the links 36 of each slide has a downwardly extending lever arm 38 in the path of which a stop 39 is arranged. When the table is extended, the lever arms 38 will strike the stops 39, thereby tilting the links 36 to an upright position, and thus projecting the extension leaf in an upward 35 direction, the parts being so proportioned that the top face of the extension leaf when thus projected will lie flush with the top face of the table top A. When the table top is collapsed, the extension leaf will grav- 40 itate to its normal position.

A suitable catch or latch device 40 is provided whereby the table drawer may be locked with relation to the inner side members of the extension slides. A suitable locking device 41 is also provided whereby the 45 extension leaf and the table top may be securely connected together to hold the parts securely in extended or collapsed relation as may be required.

From the foregoing description, taken in 50 connection with the drawings hereto annexed, the operation and advantages of this device will be readily understood. The improved extension table is simple in construction, durable, inexpensive, and easily manip- 55 60 ulated, and it will be found extremely use-

ful in flats, apartments, and other places where, owing to scarcity of room, an ordinary dining table can not well be accommodated. The table when collapsed presents the neat and attractive appearance of an ordinary library table, there being no exposed parts such as the ends of extension slides or the sides or ends of the extension leaf, to indicate the possible use thereof as a dining table. The table, of course, may be 65 made in various dimensions and more or less ornamental. It is proposed to make the extension leaf as well as the table top of built-up material which will be extremely durable and ornamental as well as light in weight. 70 It may also be stated that by the construction herein shown the table may be conveniently knocked down for storing and shipping purposes.

Having thus described the invention, what 75 is claimed as new is:

1. In an extension table, a frame, extension slides each having inner and outer side members and intermediate members, said intermediate members having their ends connected with the frame, movable side members one of which is connected with the outer side members of the extension slides, a table top having rims at the sides and ends thereof, hinges connecting one side rim of the 80 table top with the inner side members of the extension slides, and an extension leaf housed between the side and end rims of the table top; said extension leaf being connected with the outer side members of the 85 extension slides by links some of which have downwardly extending lever arms, the table frame being provided with stops lying in the path of said lever arms.

2. In an extension table, a permanent 90 frame including a blind side rail, extension slides each having an intermediate member and inner and outer side members, the intermediate members of said extension slides being connected with the permanent frame, 95 two movable side members one of which constitutes a drawer front, a table top having downwardly extending rims at the sides and ends thereof, said table top being hingedly connected with the inner side members of the extension slides, an extension leaf normally housed between the side and end rims of the table top, means whereby the extension leaf is movably connected with the outer side members of the extension slides, and means whereby said extension leaf is automatically projected in an upward direction 100 when the table is extended.

In testimony whereof I affix my signature.
JAMES FAULKNER THOMAS.
